UNITED STATES PATENT OFFICE

2,533,678

VAPORIZING TRAY TYPE OIL BURNER

Theren A. McCrimmon, Bessemer, Ala.

Application October 30, 1947, Serial No. 783,203

1 Claim. (Cl. 158—91)

1

This invention relates to oil burners of the gravity feed type.

An object of this invention is to provide an oil burner which while designed for use in tobacco drying apparatus will provide an efficient burning of oil, and can be used in boilers, furnaces or other heating equipment.

Another object of this invention is to provide an oil burner which includes a plurality of superposed shelves or trays over which the oil is adapted to flow, the excess or unburned oil engaging on an upper shelf or tray dripping onto a succeeding shelf or tray, the shelves or trays being so constructed and arranged, and of such number that all of the oil will be burned.

A further object of this invention is to provide an oil burner of this type wherein the inflowing air will effect a spreading of the oil onto the burner plates or trays and cause vaporization of the oil as the oil drips from one burner plate to another.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a longitudinal section of an oil burner constructed according to an embodiment of this invention.

Figure 2 is a sectional view taken on the line 2—2 of Figure 1.

Figure 3 is a sectional view taken on the line 3—3 of Figure 1.

Referring to the drawings, the numeral 10 designates generally a housing which is formed of top and bottom walls 11 and 12 and opposite side walls 13 and 14. The housing 10 is provided with supporting feet 15 which support the housing above a plane surface. The top wall 11 is formed with upwardly extending side flanges 16 against which the side walls 13 and 14 are adapted to be secured by any suitable fastening means and the inner end of the top wall 11 is formed with an upstanding flange 17. The housing 10 is open at each end and the front end of the housing

2

10 is adapted to be selectively closed by means of a door or hinged closure 18 which is pivotally mounted on ears 19 carried by the housing 10. The housing 10 also includes in the forward portion thereof a collecting chamber 20 which is formed by offsetting downwardly the forward portion of the housing and the chamber 20 is adapted to be connected by means of a pipe 21 to a receiver or the like. The top wall 11 has secured thereto a fuel discharge pipe 22 which is adapted to discharge fuel into the forward portion of the housing.

The side walls 13 and 14 are each formed with vertically spaced supporting flanges 23, 24 and 25 which terminate at their inner ends in upwardly projecting flanges or stop members 26, 27 and 28, respectively. An oil distributing upper plate 29 is disposed on the upper support comprising the flanges 23 and 26 and an intermediate oil distributing plate 30 is disposed on the intermediate support comprising the flanges 24 and 27. A lower oil distributing plate 31 is mounted on the lower support comprising the flanges 25 and 28 and these oil distributing plates are preferably of increasing width from the uppermost to the lowermost as shown in Figure 1. The upper surface of the plate 29 is inclined downwardly and forwardly as indicated at 32 and an oil retaining rib 33 projects upwardly from the forward edge of the plate 29. The rib 33 is of a short length and the side edges thereof terminate in spaced relation from the side walls 13 and 14. The top surface 34 of the plate 30 is inclined downwardly and forwardly and an upwardly projecting oil retaining rib 35 projects from the front portion of the plate 30. The rib 35 is of a greater length than rib 33 and the ends are spaced from the walls 13 and 14. The lower plate 31 is formed with a downwardly and forwardly projecting upper surface 36 and an upwardly projecting retaining rib 37 is carried by the front edge of the plate 31. The rib 37 is of a greater length than the rib 35 and is spaced from the walls 13 and 14. The upper surfaces of the oil distributing plates are inclined downwardly and toward the front of the housing 10 so that the oil overflowing from the upper plate 29 and dropping onto the intermediate plate 30 will by reason of the inward draft of air through narrow slots 38 formed in the door or closure 18 cause the oil to become

partially vaporized as it drops and the globules of oil which drop from one plate to the other will be carried inwardly of the housing by the force of the inwardly moving air. This inwardly moving air not only assists in distributing the oil over the surfaces of the plates 29, 30 and 31 but also provides air for mixture with the oil vapors for combustion purposes. The oil which finally drops from the lower plate 36 enters the overflow or collecting chamber 20 and from this chamber is drained to a suitable receiver.

The inner portion of the housing 10 is provided with a refractory lining 39 terminating at its inner end in a refractory flange 40 which overlies the inner end of the housing 10.

In the use and operation of this burner the oil is discharged from the fuel pipe 22 by gravity onto the upper burner plate 29. It will be understood that the supply pipe 22 may have a suitable regulating valve interposed therein for properly regulating the discharge of oil onto the upper burner plate 29. The oil may be lighted in any conventional manner and in the event there is not sufficient inflowing air entering the housing through the air intake openings 38, the door 18 may be swung partly to open position to admit additional air into the housing 10. By having the upstanding short ribs 33, 35 and 37 on the respective burner plates the dripping of unburned oil from one plate to another is retarded so that the oil on one burner plate will burn to the greatest degree possible. This burner has been designed particularly for use in tobacco drying apparatus but can be used for other purposes such as in boilers, furnaces or other heating equipment.

What I claim is:

An oil burner comprising a housing open at each end, a closure hingedly carried by the front

end of said housing formed with a plurality of vertically spaced apart horizontally elongated air intake slots, a plurality of horizontally disposed burner plates, each of said plates having the upper surface thereof inclined downwardly toward the front end of said housing and the front edges of said plates being progressively offset rearwardly from the lowermost to the uppermost plate whereby excess unburned oil on an upper plate will drip onto a lower plate, an oil supply pipe disposed above the uppermost of said plates and adapted to discharge oil thereon, an oil retaining rib carried by the front edge of each plate, each of said ribs being of less length than the width of its associated plate and of progressively increasing length from the rib on the uppermost to the rib on the lowermost of said plates whereby oil flowing on said plates is caused to flow around the ends of said ribs, means supporting said plates in superpose spaced relation and in substantial alignment with said slots whereby the air entering the housing through said slots will pass over said plates and effect a distribution of oil on said plates.

HERON A. MCCRIMMON.
